Primary Examiner — Lauren R Calve(74) *Attorney, Agent, or Firm* — Cislo & Thomas, LLP(57) **CLAIM**

The ornamental design for a tie hanger, as shown and described.

DESCRIPTION

FIG. 1 is a perspective view of a tie hanger;

FIG. 2 is a front view thereof;

FIG. 3 is a back side view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof shown in environmental use.

The broken line portions of the disclosure are included for the purpose of illustrating environment and form no part of the claimed design.

1 Claim, 6 Drawing Sheets(56)
